UNITED STATES PATENT OFFICE.

CHARLES W. H. FREDERICK, OF MELROSE, MASSACHUSETTS, ASSIGNOR TO
THE HEYWOOD BROTHERS & WAKEFIELD COMPANY, OF WAKEFIELD,
MASSACHUSETTS.

DESIGN FOR A SEAT-BACK HANDLE.

SPECIFICATION forming part of Design No. 32,746, dated May 29, 1900.

Application filed April 25, 1900. Serial No. 14,380. Term of patent 7 years.

To all whom it may concern:

Be it known that I, CHARLES W. H. FREDERICK, of Melrose, in the county of Middlesex and State of Massachusetts, have invented and produced a certain new and original Design for a Seat-Back Handle, of which the following is a specification, reference being had to the accompanying drawings, forming a part thereof.

10 In the drawings, Figure 1 represents a side view of a seat-back handle, showing my new design. Fig. 2 represents a top plan view of the same.

15 As shown in the drawings, the leading or material feature of my design consists of the outer or grip portion *a*, the inner portion *b*,

substantially parallel with the portion *a*, the connecting portions *c* and *d*, the relatively-short end portion *e*, substantially parallel with the portions *a* and *b*, and arranged out 20 of alinement with each of said portions, and the longer end portion *f*, arranged substantially at a right angle with the end portion *e*.

I claim—

The design for a seat-back handle substantially as herein shown and described. 25

In testimony whereof I have affixed my signature in presence of two witnesses.

CHARLES W. H. FREDERICK.
